Primary Examiner — John R Yeh

(57) **CLAIM**

The ornamental design for a scrubber, as shown and described.

DESCRIPTION

1.Scrubber

1.1 : Perspective

1.2 : Front

1.3 : Back

1.4 : Left

1.5 : Right

1.6 : Enlarged view of top plan view

1.7 : Enlarged view of bottom plan view

1.8 : Perspective

1.9 : Enlarged

1.10 : Enlarged

1.11 : Enlarged

1.12 : Folded state

1#Purpose of this design product: The present design product is used for cleaning; 2#Design point of this design product: The shape of the design; 3#The dash-dash broken lines in the drawings depict the portions of the scrubber which form no part of the claimed design; 4#The dot-dash broken lines in the drawings depict the boundaries of the partial enlarged views that form no part of the claimed design.

1 Claim, 12 Drawing Sheets(56)
